His Attorney.

UNITED STATES PATENT OFFICE.

WILLIAM B. TEMPLETON, OF LONG LAKE, WASHINGTON, ASSIGNEE TO GENERAL ELECTRIC COMPANY, A CORPORATION OF NEW YORK.

ELECTRIC SWITCH.

1,287,105.

Specification of Letters Patent. Patented Apr. 13, 1920.

Application filed December 12, 1916. Serial No. 186,425.

To all whom it may concern:

Be it known that I, WILLIAM B. TEMPLETON, a citizen of the United States, residing at Long Lake, in the county of Lincoln, 5 State of Washington, have invented certain new and useful improvements in Electric Switches, of which the following is a specification.

My invention relates to electric switches 10 and especially to that type of switches known as disconnecting or air break switches.

The object of my invention is to provide a novel and improved electric switch and 15 particularly to provide a disconnecting switch which can be held positively locked in its closed position but which can be automatically released and the switch easily opened by one single or continuous movement and within a minimum time.

The novel features which I believe to be characteristic of my invention will be definitely indicated in the claims appended hereto; the features of construction and 25 mode of operation will be understood by reference to the following description taken in connection with the accompanying drawings, which show the preferred embodiments of my invention, and in which—

Figure 1 illustrates my improved type of disconnecting switch embodying the novel features of my invention, Fig. 2 is a side elevation of a portion of my switch, and Fig. 3 is a top elevation of a portion of my 30 switch shown in Fig. 2.

In Fig. 1 I have shown the novel features of my invention embodied in a disconnecting switch comprising a movable switch member or contact blade 1 pivotally carried 35 and supported on an insulator 2. The contact blade 1 co-operates with a fixed contact member or contact clips 3, carried on a second insulator 4, to open and close the switch. Also carried on insulator 4 and 45 mounted adjacent and in alignment with contact clips 3, I provide means for locking the contact blade in switch closing position which consists of a locking device 5. The particular form of locking device shown is 50 not a part of my invention, being covered in the U. S. Patent 1,119,590 to Henry G. French. A brief description of this device will, therefore, be sufficient to understand the operation of the device.

This locking device comprises two arms 55 or yieldingly mounted latching members 6 biased or pressed, in any suitable way, as by a spring, to locking position for holding or locking the contact blade in switch closing position. These latching members are 60 provided with shoulders 7 which engage the contact blade 1 to hold the blade in switch closing position and have flaring extensions which enable the latching members 6 to be easily moved into releasing position. 65 The two latching members have a common pivot 8 carried on a suitable support attached to insulator 4. The latching members 6 are normally biased toward each other and into latching position by any suitable means such as springs, not shown, but which are mounted in sockets 10 and push upward against caps 11 which engage the latching members 6 and tend to turn the latching members 6 about the pivot 8. In 70 closing the switch the contact blade 1 slides frictionally between the latching members 6 pressing them apart and when the blade passes the shoulders 7, the members 6 spring into latching position and positively lock 75 the switch closed. To open the switch the latching members are pushed back against the tension of the springs away from the contact blade 1 into releasing or unlocking position so that the space between their 80 shoulders 7 is sufficient to admit the contact blade 1. The only resistance to the switch opening movement of contact blade 1 is, therefore, the frictional engagement of the shoulders 7 of the latching members on the 85 blade. When the blade is pulled out of the locking device, the latching members spring back to latching position through the action of their springs ready to catch and hold the contact blade 1 when it again moves into 90 switch closing position.

In locking devices of this character and in others known in the art, it is necessary before the switch blade can be moved to switch opening position, to first move, by 100 means of the usual wooden operating rod, the latching members of the locking device into releasing position and then move the switch blade to its open position thus necessitating two or more separate operations 105 with consequent loss of time before the switch can be opened. Locking devices have been used in which the contact blade would

ride up over the latching members when moved to switch opening position in order to eliminate the extra movement of the locking device to releasing position before 5 the switch could be opened, but such locking devices do not hold the contacts positively locked in switch closing position and are liable, therefore, to be accidentally opened under some conditions of heavy 10 short circuit existing on the feeders. I have provided a switch which possesses the advantage of being positively locked in closed position and at the same time can be released and opened with one continuous 15 movement in the same direction. To release the locking device 5 by the opening movement of the switch, I provide means operative by the switch opening movement for automatically moving the latching members 6 of the locking device 5 to releasing 20 position.

This releasing means for the locking device 5 comprises an operating member 12 pivotally supported to the contact blade 1. 25 This member is provided with an extension 13 comprising a ring opening into which the usual wooden operating rod can be inserted to operate the switch. This member, 12, therefore, serves not only as a releasing 30 member for the locking device 5 but also as a means by which the switch is operated. One end of the releasing member 12 carries, pivotally secured thereto, a shoe or wedging member 14 which co-operates with the latching members 6 to force the latching members apart and into releasing position. The other end of member 12 is provided with a portion 15 adapted to engage the contact blade 1 and transmit the thrust to the contact blade during the movement of the switch to closed position. I have shown the member 12 as pivotally supported between the two portions of a contact shoe 16 which is secured to the contact blade to make a 40 firm contact between the blade and the clips 3, but it is understood that this member may be carried by the blade in other suitable ways.

In the closed position of the switch, the 50 locking device 5 is in locking position holding the contact blade 1 locked and the releasing member 12 is in the position shown in Fig. 1. When it is desired to open the switch, the wooden operating rod is hooked 55 into the ring opening portion 13 of the operating member 12 and the movement of the operating member about its pivot in switch opening direction drives the wedge member or releasing means 14 in between 60 the latching members 6 of the locking device 5 to move them into releasing position whereupon on further movement of the releasing member the switch blade 1 is drawn out from between the latching members 6 65 and into switch opening position. Thus by

one continuous movement the locking device 5 is moved to unlocking position and the switch opened.

Should it be desired to provide a means besides the wedging member 14 to hold the latching members in releasing position while the switch is still closed, a means such as setting pawls or dogs 17 may be provided on the locking device pivoted on each latching member 6 and arranged to catch on the 70 blade 1 and thereby hold back the latching members 6 as long as the blade is in the clips 3. The dogs 17 are biased to move upward against shoulders 18 on the members 6 into a position in which their inner ends engage 75 the blade 1 when the switch is closed and thereby hold the members 6 in the releasing or inoperative position with the shoulders 7 out of alignment with the blade 1. These dogs 17 project toward each other and their 80 inner ends engage the opposite sides of the blade 1 when both members 6 are held back in the releasing position as shown in Fig. 3. The springs in sockets 10 also engage the pawls 17 to force them upward against 85 their shoulders so that in this position the members 6 and pawls 17 form practically a single unit pivoted at 8. As soon as the switch opens and the blade 1 passes out from between the inner ends of the pawls, 90 the springs throw the members 6 in against the sides of the blade 1. Further opening of the switch is not hindered except by the friction of the latches against the sides of the blade and as soon as the blade passes 95 out from between them the members 6 spring into position ready to engage and hold the blade 4 when the switch is again closed. Thus instead of having the wedging portion of member 12 hold the latching members 100 in releasing position, the wedging portion may be made to move the latching members into releasing position in which position they are held by the dogs 17 until the switch blade 1 is removed.

110 Although I have shown a locking device comprising two latching members held in open position by dogs 17, it is apparent that the dogs may be omitted if desired without affecting the essential features and operation 115 of the switch of my invention.

My invention may be embodied in other forms than that shown and described and I, therefore, do not wish to be restricted to the particular structure shown but wish to 120 cover by the appended claims all changes and modifications within the spirit and scope of my invention.

What I claim as new and desire to secure by Letters Patent of the United States is:— 125

1. In an electric switch, the combination with a movable switch member, latching members between which said switch member is movable to closed position, said members being biased to lock said switch member in 130

- closed position, a pivoted member operatively related to said switch member by means of which said switch member is moved having a portion for moving said latching members to releasing position, said latching members being released and said switch member moved to open position in response to a continuous movement of said pivoted member in one direction.
2. An electric switch, comprising a movable contact member, latching members on each side of said contact member biased to lock said contact member in closed position, means for separating said latching members to permit said contact member to move to open position, and an operating member operatively related to said contact member by means of which said contact member is movable and said releasing means is controlled, whereby said latching members are released and said contact member moved to open position in response to a continuous movement of said operating member in one direction.
3. An electric switch, comprising a movable contact member, coöperating fixed contacts, latching members on each side of said movable contact member for locking said member in closed position, an operating member operatively related to said contact member and movable in the plane of said contact member by means of which said contact member is movable, and a releasing means for said locking device pivotally supported by said operating member, whereby a continuous movement of said operating member in one direction releases said locking device and moves said contact member to the open position.
4. In an electric switch the combination with a movable switch member, of an independently mounted locking device comprising latching members biased to locking position, holding means operative by the movement of said latching members into releasing position for holding said members in releasing position as long as said switch member is in switch closing position, and means whereby said latching means is moved into releasing position and said switch member to open position in a continuous movement in one direction.
5. In an electric switch, the combination with a movable switch member, latching members on opposite sides of said switch member biased to locking position and adapted to lock said switch member in switch closing position, a movable member pivotally carried by said switch member by means of which said switch member is operated, and means carried by said movable member for moving said locking device into releasing position in response to the switch opening movement of said movable member.
6. In an electric switch the combination with a movable switch member, of a locking device comprising latching members yieldingly mounted to allow the movement of said switch member therebetween and adapted to lock said switch member in switch closing position, an operating member for said switch member, a releasing means carried by said operating member for moving said latching members into releasing position in response to the movement of said operating member in switch opening direction.
7. A locking and unlocking device for electric switches, comprising two opposed coöperating members for normally retaining the switch in locked position, and means pivotally carried by the free end of the switch and engageable intermediate of the coöperating members whereby the switch may be closed or opened by a single movement of the operating rod when engaged with the last mentioned means.
8. In an electric switch, the combination with a movable switch member, latching members between which said member is movable and adapted to lock said member in closed position, and a member operatively related to said switch member for moving said latching members to releasing position, the release of said latching members and the movement of said switch member to open position taking place in one continuous movement.
9. In an electric switch, the combination with a movable switch member, latching members between which said member is movable and adapted to lock said member in closed position, and means whereby said latching members are moved to released position and said switch member moved to open position in a single movement.
10. In an electric switch, the combination with a movable switch member, of means for locking said member in closed position comprising latching members between which said member is movable, means for unlocking said locking device carried by said switch member, said locking device being unlocked and said switch member moved to open position in one continuous movement.
11. A locking and unlocking device for electric switches comprising two coöperating members for holding the switch locked in closed position, and means whereby in a single movement said coöperating members are moved to releasing position and said switch to open position.

In witness whereof I have hereunto set my hand this first day of August, 1916.

WILLIAM B. TEMPLETON.
